(57) **CLAIM**

The ornamental design for a tissue dispenser and disposal, as shown and described.

DESCRIPTION

FIG. 1 is a front perspective view of a tissue dispenser and disposal showing my new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof; and,

FIG. 7 is a right side view thereof.

The broken line shown in the figures is included for the purpose of illustrating portions of the tissue dispenser and disposal and form no part of the claimed design.
